US0D1077350S

(12) **United States Design Patent** (10) **Patent No.:** **US D1,077,350 S**
(45) **Date of Patent:** **** May 27, 2025**

(54) **POUCH**

(71) Applicant: **Henkel AG & Co. KGaA**, Duesseldorf (DE)

(72) Inventors: **Emil Tarnowsky**, Brampton (CA); **Nihat Elbi**, Toronto (CA); **Mariusz Hildebranski**, Trumbull, CT (US)

(73) Assignee: **Henkel AG & Co. KGaA**, Duesseldorf (DE)

(**) Term: **15 Years**

(21) Appl. No.: **29/850,198**

(22) Filed: **Aug. 17, 2022**

(51) LOC (15) Cl. **28-02**

(52) U.S. Cl.

USPC **D28/8.1**

CLAIM

The ornamental design for a pouch as shown and described.

DESCRIPTION

FIG. 1 is a top, front isometric view of a first embodiment of a pouch showing the claimed design;

FIG. 2 is a bottom, rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front isometric view of a second embodiment of a pouch showing the claimed design;

FIG. 10 is a bottom, rear isometric view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof; and,

FIG. 16 is a bottom plan view thereof.

The broken lines in the figures show portions of the pouch that form no part of the claimed design.

1 Claim, 8 Drawing Sheets
